PHOTOGRAPHIC DEVELOPER

Garnet Peter Grant, Jr., Silvermine, Conn., assignor to Grant Photo Corporation, New York, N. Y.

Original application March 5, 1937, Serial No. 129,165. Divided and this application April 6, 1940, Serial No. 328,210

1 Claim. (Cl. 95—94)

This invention relates to apparatus for producing photographs and particularly to an apparatus for developing an exposed film or sensitized paper. This application is a division of application Serial No. 129,165, filed March 5, 1937, now Patent No. 2,196,586, issued April 9, 1940.

In commercial photography the labor cost in developing a picture is an important item in the price. The broad object of the present invention is to provide a developer apparatus which will be completely automatic so that when an exposed film or sensitized paper is introduced into the developer, no further manual operation is necessary, and the apparatus will deliver the film completely developed, or, in the case of direct positive paper, a finished picture.

A further object of the invention is to provide a developing apparatus in which the film will be moved in a step-by-step process to the several phases of development. A further object of the invention is to provide means to control the temperature of the developing chemicals and the time for development. A further object of the invention is to provide an apparatus so constructed that a single source of power and a single operating means will operate all the moving parts synchronously.

A further object of the invention is to provide a series of developing tanks and an apparatus associated therewith so arranged that in the event of a breakdown the apparatus can be removed and the tanks used for development by hand in the usual manner. A further object of the invention is to provide an apparatus in which the film may be fed to the developer manually or may be fed automatically in the manner disclosed in the parent application of which the present application is a division.

The invention consists of the construction, combination and arrangement of parts, as herein illustrated, described and claimed.

In the accompanying drawings, forming part hereof, is illustrated one form of the invention, in which drawings similar reference characters designate corresponding parts, and in which the same reference characters are used to designate parts corresponding to the disclosure of the parent application, and in which:

Figure 1 is a side elevation, partly broken away, showing the apparatus in operative position with the film immersed in the developing tanks;

Figure 2 is a plan view;

Figure 3 is an end elevation of the left-hand

end of Figure 1, with the parts in the same relative position as shown in Figure 1; and,

Figure 4 is a side elevation, partly broken away, corresponding to the left hand side of Figure 1, but with the parts in position when the film is removed from the developing tanks.

Referring to the drawings, 20 designates a piece of film which may be either ordinary film or direct positive paper. In order to avoid handling the paper or film 20 manually it is placed in a film holder designated generally as 56. As best shown in Figure 3, the film holder 56 comprises a transverse supporting member 57 to which are connected complementary arms 58 having their upper ends 59 bent around the supporting member 57. On the lower ends of the arms 58 are disposed complementary channel members 60 to receive the strip of film 20. The channel members 60 are perforated to permit drainage of developing chemicals.

The film holder or frame 56, carrying the film 20, is adapted to be placed in a trackway of the developing apparatus, and immersed in a tank of chemicals, then raised and moved forward to a second tank and lowered into the second tank. The process is repeated through all of the necessary baths of solutions or washes until the development operation is completed.

For the apparatus, a table or support 105 is provided on which is disposed a large tank 106. The tank 106 is provided with a drain pipe 107 to which may be removably connected an overflow pipe 108 to maintain a desired water level in the tank 106. Longitudinally of the tank 106 are disposed spacers 109 upon which are set a number of small tanks 110 to contain the various chemicals used in the several steps of developing a picture. A number of water tanks 111 are provided and one tank 111 is disposed adjacent to each tank 110. A water supply pipe 112 is controlled by an ordinary valve 113. The pipe 112 is formed with several branches which terminate in outlets 114, at the ends of the several water tanks 111. The opposite wall of each tank 111 is formed with a recess 115 to permit the overflow of water into the main tank 106.

With this arrangement a constant flow of water may be maintained from the pipe 112 and discharged through the overflow 108 and drain pipe 107. The tank 106 will fill with water to the top of the overflow 108 and will circulate around the several chemical tanks 110. In this way the temperature of the chemicals in the tanks 110 may be controlled. In cold weather where it is not desired to cool the contents of

the tanks 110, the overflow 108 may be removed and the water from the tanks 111 will flow directly into the drain 107 without circulating around the tanks 110.

Carried by the edge of the tank 106 is a horizontal angle iron frame 116. On one side of the frame 116 is provided a plurality of main vertical supporting posts 117 and on the opposite side of the frame 116 are provided complementary supporting posts 118. All of the mechanism hereinafter described is supported entirely from the frame 116 which is merely set on the edge of the tank 106 and is not secured thereto. In the event of an emergency the entire automatic developing mechanism may be lifted from the tank 106 and the various tanks 110 and 111 may be used for hand developing.

Carried by one post 117 is an electric motor 120 which supplies movement to a worm drive 121 of ordinary construction. The worm drive 121 operates a worm wheel 122. An auxiliary vertical frame member 123 is provided and is maintained rigid by a cross member 124 near its lower end. The member 123 may rest on the table 105.

A transverse shaft 125 has its ends journaled in the supports 117 and 123 and is rotated by the worm wheel 122. Carried by the shaft 125 is a cam 126 having one large extended face 127 and a plurality of small projections 128. The operation of the cam 126 causes the film frames 56 to be raised and lowered in the tanks 110 and 111, as hereinafter described. On the cam 126 there is a portion on either side of the point marked 129 on Figure 1 where there is no projection 128. This clear portion is provided so that the mechanism controlled by the cam 126 will remain stationary while frames 56 are being fed on by hand, or by means of an automatic apparatus as disclosed in Patent No. 2,196,586.

An extension 130 is provided on the post 117 and a lever 131 is pivoted at 132 to the extension 130. The opposite end of the lever 131 is connected to a twisted link 133, the upper end of which is pivoted to the mid-point of a transverse bar 134. The front end 135 of the bar 134 is connected to a longitudinal bar 136 which is rotatable and the ends of which are journaled in the two posts 117. The opposite end of the transverse bar 134 is connected to a U-shaped frame 137 having arms 138 through the center of which passes the bar 136 and to which the arms 138 are connected. A counter-balance 139 is secured to the frame 137 to permit easy movement of the parts, as hereinafter described.

To the end of each arm 138 are connected transverse U-frames 140 by means of pivots 141. The U-frames 140 are provided with depending arms 142 which support a longitudinal trackway 143. The trackway 143, as best shown in Figure 3, comprises a pair of relatively wide strips 144, one on either side of a narrow strip 145 so as to leave a space therebetween into which may be received the ends of the supporting member 57 of the frames 56.

As the cam 126 is rotated the large face 127 will ride against the lever 131 and depress the same. The lever 131, acting through the link 133 will draw downwardly the transverse bar 134. The bar 134 will carry with it the frame 137, and the arms 138 will be rotated with the bar 136. As the arms 138 rotate the frames 140 will be raised and the trackway 143 will also be raised. As the cam 126 travels further the parts

will return to their positions through gravity and the weight of the trackway 143 and frames 140. The counter-balance weight 139 is not sufficient to prevent the lever 131 from bearing against the cam 126 at all times. After the cam face 127 has passed out of contact with the lever 131 the lever will be moved to a small extent by each projection 128 as it passes. This will effect a vertical agitation of the trackway 143 for the purpose hereinafter described.

As the forward end of the arms 138 move upward to raise the trackway 143, the line of motion will be a slight arc. This will have a tendency to cause a slight swinging motion of the trackway 143 since it is suspended solely by the pivots 141. To prevent this, vertical guideways (not shown) may be provided in which the trackway 143 or the arms 142 may operate.

20 In order to advance the frames 56 along the trackway 143 a horizontal motion is provided. A vertical pitman 146 is pivoted at 147 to a bracket 148 carried by one post 117. On its lower end the pitman 146 is formed with a reduced portion 150 for the purpose of operating a lever, as hereinafter described. The pitman 146 has formed therein a longitudinal slot 151 through which is disposed a stud 153 carried by a disc 152 which is operated by the shaft 125.

30 Extending from each post 117 is a transverse support 154 having its front end supported on the post 118 by a short angle iron 155. A longitudinal bar 156 has its ends 157 bent around the transverse supports 154. Carried by the supports 154 are blocks 158 on either side of the ends 157 so that the bar 156 is free to slide longitudinally of the apparatus.

35 A lever 159 is carried on a pivot 160 on one transverse support 154. One end 161 of the lever 40 159 is bifurcated to receive the reduced end 150 of the pitman 146. The opposite end 162 of the lever 159 is also bifurcated and engages a pin 163 carried on one of the bent ends 157 of the bar 156. Depending from the bar 156 are a plurality of angle members 164 adapted to engage behind the frames 56, to push the same along the trackway 143. The initial angle member 165 is slightly curved, as best shown in Figure 1, so that it may more readily engage a frame 56 if 45 the same is not in proper position.

50 As the cam 126 rotates, the disc 152 will rotate therewith and the pitman 146 will move back and forth through the action of the stud 153 in the slot 151. As the cam face 127 engages the lever 131 the trackway 143 will be raised to the position shown in Figure 4. At that time the stud 153 will be in the upper part of the slot 151 and further movement will cause the pitman 146 to move to the left from the position shown in Figure 1. This movement will rock the lever 159 and move the bar 156 toward the right. Any frames 56 which are in the trackway 143 will lie in the path of movement of the angle members 164 or the initial angle member 165. 55 Upon movement of the bar 156 the frames 56 will be advanced from a position over one tank 110 to a position over the succeeding tank 111.

60 As the cam face 127 passes the lever 131 the trackway 143 will again be lowered and the frames 56 immersed in the several tanks. As the cam 126 continues to turn, the pitman 146 will be moved from left to right causing the bar 156 to return toward the left to its normal position.

65 It will be noted that the tanks 110 are twice

as wide as the water tanks 111. The purpose of this construction is to permit the film 20 to be immersed twice in each tank 110 and only once in the wash tanks 111. As the frame 56 is moved on the trackway 143 by the members 164 the frame will be moved from the left-hand to the right-hand side of each tank 110. On the next step the frame 56 will be moved into position to be immersed in a wash tank 111. As the various projections 128 on the cam 126 pass the lever 131, the trackway 143 will be raised and lowered slightly. This will not be sufficient to withdraw the film 20 from the various tanks but will effect a desirable agitation of the frame 56 and the film 20.

In the operation of the apparatus the frames 56 are fed to the trackway 143 by inserting the ends of the member 57 into the complementary slots in the trackway 143 formed by the strips 144 and 145. Where the frames 56 are fed automatically it is desirable that they be fed to the trackway 143 during the time when the portion 129 of the cam 126 is in engagement with the lever 131, all as disclosed in Patent No. 2,196,586. Where the frames 56 are fed to the trackway 143 manually, they may be applied at any stage, regardless of the position of the trackway 143. It is only necessary to insert the frames 56 far enough on the trackway so that they will be engaged by the initial member 165. If desired, more than one frame 56 may be fed to the trackway at one time and the several frames will be moved along the trackway by a single member 164. As the frames 56 are moved by the last member 164 on the right hand end of the bar

156, they will pass the right-hand end of the trackway 143 and fall into a chute 180 which may communicate with any desired receptacle to receive the frames 56. The film 20 is then removed and the frame 56 is ready for re-use.

5 Since the entire apparatus is controlled by the operation of motor 120 and the driving member 121, the duration of the development may be readily controlled by varying the speed of the driving member in any conventional manner. 10 The time of the developing process will vary with the conditions under which the work is being done.

15 Having thus fully described the invention, what is claimed as new and desired to be secured by Letters Patent is:

20 In a photographic film developing apparatus of the type having a plurality of fluid containing tanks, the combination of a trackway extending over the tanks and adapted to support a film holder having a film thereon, a pivotally mounted frame having the trackway pivotally connected therewith, said frame being rockable to lower and raise the trackway and lower the holder and film into and raise the same out of said tanks, 25 means for moving the film holder and film along the trackway from one tank to another when said trackway is raised, said film holder moving means comprising a slidably mounted bar provided therealong with film holder engaging elements, driving means, a shaft driven by said driving means, a cam for rocking said frame and driven by said shaft, and means actuated by the shaft for reciprocating said bar.
